SEWING MACHINE SAFETY DEVICE

Alfred R. Wood, Bridgeport, Conn., assignor to
The Singer Manufacturing Company, Elizabeth, N. J., a corporation of New Jersey

Application August 21, 1945, Serial No. 611,721

12 Claims. (Cl. 112—219)

1

This invention relates to sewing machines and more particularly to a cyclically operable sewing machine having a clamp for holding the work and which machine performs a sequence of operations and then comes to rest with its parts in predetermined positions.

Machines of this type are usually placed on a table and are driven from any suitable source of power through a start and stop motion mechanism which starts the machine at the beginning of the cycle and arrests its action at the completion of the cycle. These machines each comprise stitch-forming mechanism and a work-holding clamp movable relative to each other to cause a group of stitches to be formed. Thread cutters are provided for trimming the upper and lower threads and a work-clamp lifting means is associated with the machine for the purpose of raising the clamp for insertion and removal of the work. The start and stop motion mechanism and the clamp lifting means are usually controlled by the operator's feet and, if the operator depresses the clamp-lifting treadle before the machine has come to rest, the thread cutters will move across the needle-path and break or bend the needle.

Further, if the work-clamp is opened to release the work before the final stitch is set, the proper action of the stitch-forming mechanism is interfered with and the last stitch will not be properly set. Operators, in an effort to obtain maximum production try to anticipate the action of the stitch-forming mechanism and sometimes prematurely depress the work-clamp opening treadle which raises the work-clamp just prior to the time the start and stop motion brings the machine to rest and this causes the thread cutters to move laterally against the needle which has not yet been raised clear of the work. Sometimes the operator will depress the starting treadle before the work-clamp is in proper position. When this occurs the work is spoiled and the machine damaged.

The principal object of the present invention is to overcome the above described difficulties and to provide an improved safety device for sewing machines of the cyclically operable type which will prevent damaging the machine and the work and which will positively prevent the operator from lifting the work-clamp until the stop motion mechanism has brought the machine to rest. This invention also contemplates an improved interlocking mechanism which will prevent the starting of the machine until the work-clamp

2

and thread cutters have been released and have assumed their normal positions.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 is a right side elevational view of a straight buttonhole sewing machine equipped with the present invention.

Fig. 2 is a rear elevational view of the machine, showing in addition the two foot-operated treadles, one for raising and lowering the work-clamp and the other for starting the machine.

Fig. 3 is a top plan view, partly in section, of the machine-bed, illustrating the work-clamp and its actuating mechanism and the needle-thread trimmer and its operating connections.

Fig. 4 is a fragmentary right side elevational view of the machine, showing the operating positions of the interlock elements when the work-clamp is in lowered or work-clamping position and the tilting stop-motion lever is in machine-running position.

Fig. 5 is a view similar to Fig. 4, but with the work-clamp raised and the tilting stop-motion lever in machine-stop position, illustrating the manner in which the interlock lever functions to prevent the stop-motion lever from being manually swung into machine-running position.

Fig. 6 is a fragmentary right side elevational view, illustrating the stop-motion lever just after it has swung into machine-stop position and the way in which this action of the stop-motion lever turns the interlock-latch-pawl outwardly in preparation for its subsequent connection with the spring-biased stop-motion plunger.

Fig. 7 is a fragmentary view of certain of the parts in Fig. 6, showing how the interlock-latch-pawl swings inwardly into a position overlying the stop-motion plunger cross-bar when the stop-motion plunger is depressed by the stop-cam, so that when the stop-motion plunger snaps into the stop-notch provided in the stop-cam, the interlock latch will be retracted from beneath the work-clamp lifting stud.

Referring to the drawings, the machine chosen for the purposes of the present disclosure is a so-called straight buttonhole machine and has a frame including a bed 10 from which rises a

standard 11 of the bracket-arm 12 terminating in a head 13. Journaled in the bracket-arm 12 is a main-shaft 14 connected within the head 13 to the usual endwise reciprocatory and laterally vibratory needle-bar 15 carrying a needle 16. Complemental to the needle in the formation of lock-stitches is a loop-taker (not shown) adapted to be driven by a bed-shaft 17 operatively connected to the main-shaft 14 by gearing 18 and a vertical shaft 19 disposed in the standard 11. Power is applied to the main-shaft 14 by a driving belt adapted to run upon a nest of pulleys 20 carried on a countershaft 21 journaled on the bracket-arm 12 and connected to the main-shaft 14 by gearing 22 in a manner fully disclosed in my U. S. Patent No. 2,338,611, issued January 4, 1944.

The work to be buttonholed is adapted to be held in a work-clamp comprising the usual lower work-plate 23 and an upper clamp-foot 24. The upper clamp-foot 24 is carried by the two resilient arms 25 which are secured at their inner ends on a yoke 26 pivoted at 27 to a lug 28 upstanding from the usual longitudinal slide-plate 29. The upper clamp-foot 24 is yieldingly urged downwardly into contact with the lower work-plate 23 by a coil-spring 30. To provide for separating the upper clamp-foot 24 from the lower work-plate 23 for the insertion and removal of work, the yoke 26 is formed with a rearwardly extending tail-lever 31 adapted to underlie a roller 32 clamped for limited vertical adjustment intermediate the ends of a manually actuated clamp-lifting lever 33 fulcrumed at one end on a stud 34 threaded into the supporting bracket 35. At its other end, the lever 33 is fitted with a horizontally disposed stud 36 to the free end of which is attached a suitable connection-element 37 having fastened to its lower end a chain 38 connected to a foot-operated treadle 39 (Fig. 2). Depression of the treadle 39 will cause the lever 33 to swing on the stud 34, against the action of a spring 40, thus causing the roller 32 to engage the tail-lever 31 and swing the yoke 26 about its fulcrum 27, thereby raising the arms 25 and the upper clamp-foot 24.

To effect shifting of the work relative to the endwise reciprocatory and laterally vibratory needle 16, the work-clamp is slowly moved in step-by-step fashion, first away from the standard 11 and then towards the standard to cause the first and second rows of side zigzag stitches to be laid side by side in the work. The work-clamp derives its step-by-step movements from the usual feed-cam 41 (Fig. 1) carried at the lower end of a vertically disposed feed-shaft 42 journaled in the bed and the bracket-arm of the machine. The connections between the work-clamp and the feed-cam are identical with those disclosed in my United States Patent No. 2,411,493, issued November 19, 1946, as are also the means employed for intermittently rotating the feed-shaft 42 and the feed-cam 41. Therefore, a description herein of those mechanisms of the present machine is not deemed necessary.

As is customary in group-stitch sewing machines of the type disclosed, there is provided a needle-thread cutter and a bobbin-thread cutter. The needle-thread cutter, which is best illustrated in Fig. 3, and which forms the subject of my U. S. Patent No. 2,426,543, dated August 26, 1947, comprises a compound thread-cutting and -nipping blade 43 mounted upon the lower end of a vertical shaft 44 journaled in the upper clamp-foot 24. Secured to the upper end

of the shaft 44 is a crank-arm 45 connected with one end of a push-rod 46 disposed in the direction of longitudinal movement of the work-clamp and endwise slidably supported in an ear 47 bent upwardly from the yoke 26. The ear 47 also serves in conjunction with a fixed collar 48 upon the push-rod 46 as a stop to limit the endwise motion of the rod under the action of a spring 49 connected at one end with the ear 47 and at the other end with a second collar 50 fixed on the push-rod 46. The previously mentioned feed-shaft 42 is made use of to control the necessary endwise movements of the push-rod 46, first, to effect the release of the nipped beginning end of the needle-thread, second, to set the compound cutter and nipper blade 43 preparatory to the retrimming of the beginning thread-end and, third, to reset the blade 43 preparatory to the trimming of the finishing end of the needle-thread and nipping the beginning end of the needle-thread for the beginning of the next sewing operation. The feed-shaft 42 (Fig. 3) has adjustably fastened thereon a cam 51 which is adapted to rotate with the feed-shaft into engagement with a follower-nose 52 formed on a lever 53, which lever 53 is connected by a link 54 to a second lever 55 of which the free end is adapted to swing into engagement with a block 56 clamped on the push-rod 46. The cam 51, through the linkage just described, actuates the push-rod 46 in a manner such that the above mentioned first and second operations are performed. The third operation is effected through a second cam 57 which is preferably integral with, but spaced vertically above, the cam 51. The second cam 57 actuates the linkage including a two-arm lever 58 and a bell-crank lever 59 of which one of its limbs is disposed to swing into engagement with the block 56 on the push-rod 46. The second cam 57 and its linkage are proportioned so that the push-rod 46 is shifted endwise against the action of the spring 49 sufficiently far to permit a spring-influenced latch-lever 60 to drop into a stop-notch 61 formed in the collar 48. The latch-lever 60 thus maintains the compound cutter and nipper blade 43 in reset position preparatory to the trimming of the finishing end of the needle-thread and nipping the beginning end of the needle-thread for the beginning of the next sewing operation.

The latch-lever 60 is actuated to release the push-rod 46 and permit the cutter and nipper blade 43 to perform its final thread-cutting and nipping operation by a tripping element 62 secured to a link 63 adapted to be actuated by the work-clamp raising mechanism. It will be observed in Fig. 1 that the link 63 is connected, as at 64, to a vertically disposed rock-lever 65 pivoted at 66 to the bed 10. Formed adjacent the upper end of the rock-lever 65 is a cam-slot 67 having an actuating portion 68 and a dwell-producing portion 69, which cam-slot is entered by the stud 36 to which is connected the work-clamp raising foot-treadle 39. The cam-slot 67 is preferably formed with an actuating portion and a dwell-producing portion so that the link 63 is actuated only during the initial depression of the work-clamp raising foot-treadle and during the time that the stud 36 is tracking the actuating portion 68, to insure that the thread-severing means is operated before the work-clamp is raised to release the work.

The link 63, in addition to releasing the latch 60 to enable the needle-thread cutter to perform its final thread-cutting and nipping operation,

also is connected to actuate the bobbin-thread cutter, whereby the two sewing threads are cut simultaneously. As will be seen in Fig. 3, the link 63 at its forward end is connected to the shorter limb of a bell-crank lever 70, the longer limb of which is operatively connected to a cross-slide 71 formed with a rack 72. The rack 72 meshes with teeth 73 segmentally formed in a portion of the periphery of a carrier 74 to which is detachably secured a bobbin-thread pull-off finger 75 and a thread-cutting blade 76. The constructive features of the disclosed bobbin-thread pull-off and cutting mechanism are fully shown in my co-pending application Serial No. 611,725 filed August 21, 1945 and, therefore, no further description in this case of the details of this mechanism is deemed necessary. Suffice it to say that the initial actuation of the work-clamp raising foot-treadle 39, through the stud 36, swings the lever 65 forwardly, thus endwise moving the link 63 so that the tripping element 62 engages the latch 60, thereby releasing the needle-thread cutter for its final thread-cutting and nipping action, and simultaneously pivots the bell-crank lever 70 which actuates the cross-slide 71 to oscillate the carrier 74 supporting the bobbin-thread pull-off finger and cutting blade, thereby to pull-off a measured length of bobbin-thread from the supply to be used in the next buttonhole and sever the bobbin-thread leading to the last stitch in the buttonhole.

To provide means for stopping the machine at a predetermined final position, there is provided a common form of start and stop motion mechanism, the constructive features of which are fully illustrated and described in my previously mentioned U. S. Patent No. 2,338,611. Referring to Figs. 1 and 2, it will be seen that the standard 11 has fastened to it a bracket 77 having upwardly projecting spaced arms for the trunnion-screws 78 which support a tilting stop-motion lever 79. Mounted to slide vertically in the stop-motion lever 79 is the usual stop-plunger 80 which is pressed upwardly by a spring 81 for cooperation with a double notched stop-cam 82 mounted on the countershaft 21 and having eccentric stop-plunger depressing portions 83 followed by stop-and rebound-preventing notches 84. When the stop-motion lever 79 is in running position (see Fig. 4), the upper end of the plunger 80 is disposed forwardly of the stop-cam 82 and is out of range of the latter. When the stop-motion lever 79 assumes its stopping position (see Figs. 1 and 2) the plunger 80 is moved to a position under or within range of the cam 82, whereupon the eccentric portion 83 of such cam first depresses the stop-plunger 80 against the force of the spring 81 and then releases the plunger as the latter rides off the end of the eccentric portion 82 and is projected upwardly into the stop-notch 84. The stop-motion lever 79 is held in its running position by means of a spring-biased latch-lever 85 which enters a notch 86 in the side of a rod 87 controlled by a foot-treadle 88; the rod 87 being connected at its upper end to the free end of an actuating arm 89 rigid with the stop-motion lever 79. The latch-lever 85 is adapted to be acted upon by a suitable tripping element 90 carried by the feed-cam 41; releasing of the latch-lever 85 permitting a coil-spring 91 surrounding the treadle-controlled rod 87 to swing the stop-motion lever 79 with its plunger 80 toward and into the range of the stop-cam 82.

Considering now the improved safety devices of the present machine which form the subject of

this case, it will be understood from the above description, taken in connection with the accompanying drawings, that whenever the foot-treadle 39 is manually depressed the clamp-lifting lever 33, through the rock-lever 65 and link 63, actuates the needle-thread trimmer and the bobbin-thread trimmer. It will be further understood that if the opening of the work-clamp is effected prematurely, the needle 16 may be in 10 the work in which case the thread-cutting blades 43 and 76 will strike the needle as they swing to sever the sewing threads. To eliminate this condition, means is provided to prevent the opening of the work-clamp until the end of the stitching cycle. This means comprises a safety lever 92 of the first order, which lever is fulcrumed intermediate its ends on a bracket 93 secured on the bed 10. The forward end 94 of the lever 92 is disposed to underlie the work-clamp lifting lever 33, while its other end is notched to provide a cam-wall 95 adapted to be engaged by a roller 96 freely journaled on a stop-motion lever extension 97. It will be seen in Fig. 1 that when the machine is not running, in which case the stop-motion lever 79 is in its normal vertical stopping position, the roller 96 is disposed so that the safety lever 92 assumes a position in which its forward end 94 is spaced from the work-clamp lifting lever 33. When the safety lever 92 is so spaced, 20 the treadle 39 can be depressed to open the work-clamp without any resistance from the lever 92. Fig. 5 illustrates the position of the parts when the work-clamp is opened. However, when the stop-motion lever 79 is tilted into its running position as shown in Fig. 4, the roller 96 engages the cam-wall 95 of the lever 92 and swings it about its fulcrum in a manner to bring its rearward end into a position underlying the roller 96 and to bring its forward end 94 up into substantial engagement with the bottom of the work-clamp lifting lever 33. When the safety lever 92 is in the position shown in Fig. 4, the work-clamp cannot be opened, inasmuch as the forward end 94 of the lever 92 functions as an abutment and 30 precludes the lowering of the work-clamp lifting lever 33. The lever 92 is effective to prevent the premature opening of the work-clamp as long as the stop-motion lever 79 is in its running position, as shown in Fig. 4. Also, as clearly shown 35 in Fig. 5, the lever 92 is effective to lock the stop-motion lever 79 in its stopping position during the time that the work-clamp is opened.

As previously explained the stop-motion lever 79 is spring returned from its running position, 40 shown in Fig. 4, to its stopping position, shown in Fig. 6, when the latch-lever 85 is released by the tripping element on the feed-cam 41. Following the release of the stop-motion lever 79, the machine continues to operate for substantially half a revolution of the countershaft 21, during which time the needle is on its last up-stroke. During the half revolution of the countershaft 21, the stop-plunger 80 is depressed by the eccentric cam 83 and the stop-notch 84 is 45 brought into register with the stop-plunger which thereupon is projected into said stop-notch to lock the machine. During this half revolution of the countershaft, the safety lever 92 is positioned as shown in Fig. 6, in which position the work-clamp can be opened. If, however, the work-clamp is opened during this period, the thread-cutting blades 43 and 76 would strike the needle. In order to defer the opening of the work-clamp until the needle has been withdrawn a safe distance from the work, I have provided

a safety-latch-member 98 pivoted, as at 99, to the vertically-disposed rock-lever 65. The latch member 98 is formed with an abutment-ledge 100 which, as shown in Fig. 6, is adapted to underlie the stud 36 and prevent the lowering of the work-clamp lifting lever 33 when the lever 92 is in the position illustrated. In order to swing the latch-member 98 from its effective position, shown in Fig. 6, to its ineffective or inoperative position, shown in Fig. 1, I have connected to the upper end of the latch-member a link 101 which is attached to the depending and offset limb 102 of a bell-crank lever 103 pivoted on a supporting stud 104 threaded into the standard 11. The bell-crank lever 103 is adapted to be turned about the supporting stud 104 by a pawl 105 pivoted to the bell-crank lever and disposed to cooperate with a cross-bar 106 adjustably clamped to the stop-plunger 80, Fig. 3, by the set-screw 107.

The safety latch-member 98 is controlled in the following manner. Beginning with the parts in the position as illustrated in Fig. 6, in which position the latch-member 98 is effective to prevent the opening of the work-clamp, the stop-motion lever has just been released and has sprung into its stopping position, wherein the stop-plunger 80 is about to be engaged by the eccentric portion 83 of the stop-cam 82. As the stop-cam 82 continues to rotate, the stop-plunger is depressed, causing the cross-bar 106 secured thereon to be lowered beneath the shoulder 108 of the pawl 105. In response to a coil-spring 109, the pawl 105 snaps into a position determined by a stop-screw 110, see Fig. 3, in which position the pawl 105 is disposed to be engaged by the cross-bar 106 as the latter springs upwardly with the stop-plunger when the latter projects into the stop-notch 84 of the stop-cam 82. The upward movement of the stop-plunger 80 into the stop-notch 84 through the pawl 105, turns the latch-member 98, against the action of a coil-spring 111, about its pivot 99 from its effective position shown in Fig. 6 to its ineffective position shown in Fig. 1. Inasmuch as the latch-member 98 remains in its effective position until the stop-plunger enters the stop-notch 84 in the stop-cam 82, the work-clamp cannot be opened after the stitching has been completed and until the needle on its last upstroke has been withdrawn from the work.

When the machine is stopped with the parts in the positions shown in Fig. 1, the stop-plunger 80 is in the stop-notch 84 and the pawl 105 is bearing against the stop-screw 110 and is engaged by the cross-bar 106, thus maintaining the bell-crank lever 103, in opposition to the coil-spring 111, in a position such that the latch-member 98 is in ineffective or inoperative position. When it is desired to start the machine, the stop-motion lever 79 is tilted into running position, as shown in Fig. 4. The tilting of the stop-motion lever 79 causes the cross-bar 106 to move to the left (Fig. 4) from beneath the shoulder 108 of the pawl 105, thus disconnecting the bell-crank lever 103 from the stop-plunger 80 and permitting the coil-spring 111 to swing the bell-crank lever in a clockwise direction to pivot the latch-member 98 relative to the rock-lever 65 and thereby position its abutment-ledge 100 beneath the stud 36. The inclination of the abutment-ledge 100 is such as to permit easy movement of the latch-member 98 beneath the stud 36 but approaches the horizontal sufficiently close as to eliminate the effect of any reactionary force which would tend to swing the latch-member out of effective position should the

operator apply excessive pressure on the foot-treadle 39. It will be understood that in the event the operator, in anticipating the ending of the stitching cycle, prematurely applies pressure on the work-clamp lifting treadle 39, this pressure will not prevent the safety latch-member 98 from being withdrawn from beneath the stud 36. This advantage is attained by virtue of the fact that the cross-bar 106, when the stop-plunger 80 is fully depressed, is spaced below the shoulder 108 on the pawl 105 as shown in Fig. 7, thus enabling the cross-bar 106 to hit the shoulder with a sharp blow when the stop-plunger is released to project into the stop-notch 84. The blow thus applied to the pawl 105 is adequately sufficient to retract the latch-lever 98 at least beyond a point vertically beneath the center of the stud 36, after which the pressure on the treadle 39, through the cam action of the curved bottom surface of the stud 36 on the latch-member 98, will expedite the retraction of the latch-member into its ineffective position. In other words, the improved safety means will operate efficiently whether or not the operator prematurely applies pressure on the work-clamp lifting treadle.

It will be understood from the above description that the safety latch-member 98 and its controlling mechanism are designed so that the safety latch-member is effective throughout the entire stitching cycle up to and including that part of the last upstroke of the needle in which the needle is disposed in the work. In fact, the safety latch-member 98 is not shifted into its ineffective position until the needle on its last upstroke is well above the top of the work, thus making it impossible for the thread-cutting blades to strike the needle. While the safety lever 92 is effective to prevent the opening of the work-clamp when the stop-motion lever 79 is in machine-running position, it is also operative when the work-clamp is opened to prevent the shifting of the stop-motion lever 79 from its stopping position to its running position. The two safety elements 92 and 98 operate in such a way as to maintain the work-clamp and thread-cutting mechanisms locked during the sewing and are not unlocked until the stop-plunger 80 has been projected fully into the stop-notch 84 and the machine finally brought to rest at the completion of the last revolution of the main-shaft with the needle out of the work. The machine and its product are thus fully safeguarded against damage by a premature operation of the parts adjacent the sewing point.

Having thus set forth the nature of the invention, what I claim herein is:

1. In a sewing machine adapted to perform a sequence of operations and come to rest in a predetermined position, in combination, driving mechanism for said machine including a start-and-stop-motion mechanism, manually controlled means for initiating operation of the machine, a work-clamp, means for raising and lowering said work-clamp, and means under control of said start- and stop-motion mechanism for preventing said work-clamp from being raised while the machine is in operation and for preventing the initiation of the beginning of the sequence of operations when the work-clamp is raised, said last-named means including a pivot-lever of the first order with its ends cooperating with the start- and stop-motion mechanism and the clamp lifting means, and a pivoted latch under control of the start- and stop-motion mechanism and

shiftable into and out of the path of movement of said clamp lifting means.

2. A sewing machine having, in combination, stitch-forming mechanism, a work-clamp, a start- and stop-motion device including a tilting stop-motion lever, a manually operable lever for raising and lowering said work-clamp, a safety-lever pivoted between its ends and having one end underlying said manually operable lever for direct engagement therewith and its other end formed with a cam-wall adapted for cooperation with said tilting stop-motion lever, whereby when the stop-motion lever is swung to start the machine the manually operable clamp lifting lever is locked against movement and when the manually operable clamp lifting lever is depressed the tilting stop-motion lever is locked against movement.

3. A group-stitch sewing machine having, in combination, stitch-forming mechanism including a needle, a work-clamp, a manually operable lever for raising and lowering said work-clamp, a start- and stop-motion mechanism including a movable stop-motion lever for arresting the operation of the machine at the completion of a predetermined group of stitches, first safety-means controlled by said stop-motion lever and cooperating with said manually operable lever for preventing the opening of said work-clamp during the entire group-stitching cycle up to and including that portion of the last upstroke of the needle in which the needle is in the work, and an independent second safety means rendered operative when the work-clamp is open for locking said start-and-stop motion in machine-arresting position.

4. A group-stitch sewing machine having, in combination, stitch-forming mechanism including a needle, a work-clamp, a manually operable lever for raising and lowering said work-clamp, a start- and stop-motion mechanism including a movable stop-motion lever for arresting the operation of the machine at the completion of a predetermined group of stitches, safety-means controlled by said stop-motion lever and cooperating with said manually operable lever for preventing the opening of said work-clamp during the entire group-stitching cycle up to and including that portion of the last upstroke of the needle in which the needle is in the work, and an independent safety-means under control of said work-clamp lifting lever and engageable with said movable stop-motion lever for preventing the starting of the machine while the work-clamp is open.

5. A group-stitch sewing machine having, in combination, stitch-forming mechanism including a needle, a work-clamp, a manually operable lever for raising and lowering said work-clamp, a start- and stop-motion mechanism including a movable stop-motion lever for arresting the operation of the machine at the completion of a predetermined group of stitches, a safety latch-member controlled by said stop-motion lever and cooperating with said manually operable lever for preventing the opening of said work-clamp when the stop motion lever is in running position, and an independent safety-means including a pivotally supported lever under control of said work-clamp lifting lever and engageable with said movable stop-motion lever for preventing the movement of said stop-motion lever to running position while the work-clamp is open.

6. In a cyclically operable sewing machine, a

start- and stop-motion mechanism, a work-clamp, a lever for raising and lowering said clamp, a stud carried by said lever, a latch-member shiftable into and out of the path of movement of said stud, and means under control of said start- and stop-motion mechanism for determining the position of said latch-member.

7. In a cyclically operable sewing machine, a start- and stop-motion mechanism, a work-clamp, a lever for raising and lowering said clamp and carrying a stud, a member formed with a cam-slot through which said stud extends, a shiftable latch-member for locking said stud at one end of said slot, and means connecting said start- and stop-motion mechanism with said latch for controlling the position of said latch-member.

8. In a cyclically operable sewing machine having stitch-forming mechanism including a thread-carrying needle, a start- and stop-motion mechanism, a work-clamp, a manually actuated lever for opening said work-clamp and having a stud, thread-severing mechanism, an actuating member connected with said thread-severing mechanism and formed with a cam-slot through which said stud extends, a shiftable safety latch-member for locking said stud at one end of said cam-slot, and means connecting said start- and stop-motion mechanism with said latch-member for moving said latch-member into stud-locking position when said start- and stop-motion mechanism is shifted into running position, thereby to prevent premature opening of the work-clamp and operation of the thread-severing mechanism.

9. A group-stitch sewing machine having, in combination, stitch-forming mechanism including a thread-carrying needle, a start- and stop-motion mechanism including a notched stop-cam and a movable stop-motion lever having a stop-plunger adapted to enter a notch in said cam to stop the machine, a work-clamp, a manually actuated lever for opening said work-clamp and carrying a stud, thread-severing mechanism, means for actuating said thread-severing mechanism including a member formed with a cam-slot tracked by said stud, a shiftable safety latch-member for locking said stud at one end of said cam-slot, a spring for biasing said latch-member into stud-locking position, and means for moving said latch-member out of stud-locking position at the completion of the stitching operation, said last named means including a pawl adapted to be releasably connected with said stop-plunger and actuated thereby to move the latch-member out of stud-locking position during the time that the stop-plunger is entering the notch in said stop-cam.

10. A group-stitch sewing machine having, in combination, stitch-forming mechanism including a thread-carrying needle, a start- and stop-motion mechanism including a notched stop-cam and a movable stop-motion lever having a spring-pressed stop-plunger adapted to enter the notch in said stop-cam to stop the machine, a work-clamp, thread-cutting mechanism, a manually controlled mechanism for opening said work-clamp and actuating said thread-cutting mechanism including a shiftable element, a latch-member for locking said shiftable element against movement, a spring for biasing said latch-member into its element-locking position, and means for moving said latch-member out of its element-locking position, said means including a lever, a pawl for connecting said lever to said stop-plunger whereby said lever is actuated when the stop-plunger enters the notch

in said stop-cam, and means for disconnecting said pawl from said stop-plunger when the latter is moved into machine-running position.

11. In a sewing machine of the buttonhole type having a main-shaft, sewing and work-clamping means driven by said main-shaft, work-clamp opening means, and a start- and stop-motion device including a manually shiftable starting element applied to the machine to control the period of operation of said main-shaft; the provision of a single lever-member of the first order having one of its ends disposed to be engaged by one of the components of the work-clamp opening means when said work-clamp is opened and its other end notched to engage said manually shiftable starting element to prevent movement of said starting element to running position when said work-clamp is open.

12. A sewing machine having, in combination, a stitch-forming mechanism, a work-clamp, a start- and stop-motion device including a tilting stop-motion lever, a manually operable lever for raising and lowering said work-clamp, and a

safety-lever pivoted between its ends and having one of its ends underlying said manually operable lever and disposed for direct engagement therewith and the other of its ends disposed for direct engagement with said tilting stop-motion lever, said safety-lever being constructed and arranged so that when said tilting stop-motion lever is swung to start the machine the safety-lever is pivoted about its support into position to block movement of said clamp-lifting lever and when the manually operable clamp-lifting lever is depressed the safety lever is oppositely pivoted about its support into engagement with said tilting stop-motion lever thereby to lock it against movement.
